UNITED STATES PATENT OFFICE.

OSCAR HOCHBERG, OF NEW YORK, N. Y., AND JOHN W. STEINMEYER, OF EAST ORANGE, NEW JERSEY, ASSIGNORS TO AMERICAN CAR AND FOUNDRY COMPANY, OF ST. LOUIS, MISSOURI, A CORPORATION OF NEW JERSEY.

UNCOUPLING DEVICE.

Application filed March 8, 1921. Serial No. 450,770.

To all whom it may concern:

Be it known that OSCAR HOCHBERG and JOHN W. STEINMEYER, residing at New York, in the county and State of New York, and in East Orange, in the county of Essex and State of New Jersey, respectively, and being citizens of the United States, have invented certain new and useful Improvements in an Uncoupling Device, of which the following is a full, clear, and exact description, such as will enable others skilled in the art to which it appertains to make and to use the same, reference being had to the accompanying drawings which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a plan view of our invention as applied to an end sill of a railway car, portions of the sill being removed to better illustrate the manner of mounting the device;

Figure 2 is an elevational view of a car end equipped with our device;

Figure 3 is an end view of the device taken on line 3—3 of Fig. 1; and looking in the direction indicated by the arrow; and

Figure 4 is a vertical sectional view taken on line 4—4 of Fig. 1 looking in the direction indicated by the arrow.

The invention relates to that class of uncoupling mechanisms for flat and other low platform cars in which the coupler pin is directly engaged by a lever member of the mechanism without the use of chains or other connecting devices.

The principal object of our invention is to so dispose the parts thereof as to provide sufficient clearance and space for the application of pressure retaining valves, brake masts, grab irons and other appliances forming the customary grouping of devices in accordance with Interstate Commerce Commission and American Railway Association requirements.

A further object is to distribute the stresses of operation of the mechanism over a greater car end area than heretofore.

A still further object is to provide an ar-

angement in which all of the parts are positioned below the floor line of the car.

In said drawings, 10 represents one form of car end shown as comprising a member 11 of channel form cut out at 12 to receive shank 13 of a coupler 14 and carrying the usual push pole pockets 15, grab iron 16, brake mast 17, and pressure retaining valve 18. Below the upper flange 19 of the channel end 11, and on opposite sides of the coupler 14, is secured the uncoupling mechanism comprising operating lever 20 and pin lever 21 hereinafter to be described.

The mechanism is mounted in brackets 22 and 23 carrying the operating lever 20, and in bracket 24 supporting the pin lever 21, all of said brackets being secured preferably to the web 25 of the channel member 11. The operating lever 20 is provided at one end with a depending handle 26 and at its opposite or inner end with an outstanding crank arm 27. Traversing crank arm 27 is the pin lever 21 fulcrumed at one end on bracket 24 and extending with its opposite or inner end through the eye of the coupler pin 28.

It will be noted that the pin lever 21 is fulcrumed on the bracket 24 located on the side of the car end remote from the group of appliances above identified and on the opposite side of the coupler. This disposition of the pin lever is made to avoid restriction in the selection of fulcrum point location, a condition unavoidable in cases where the pin lever 21 is fulcrumed between brackets 22 and 23. It is conceivable that with the grouping of pin lever 21 on the same side of the car end with the operating lever 20, bracket 22, grab iron 16, brake mast 17, and pressure retaining valve 18, there would remain but little choice in the matter of space for the fulcrum bracket 24 carrying pin lever 21. In such environment the proportion and desirable operating relation of the levers 20 and 21 are not always attainable because of the relatively fixed positions of the safety appliances established in accordance with the Interstate Commerce Commission rulings and American Railway Association recommendations aforesaid.

By positioning the pin lever fulcrum away from the operating lever crank arm 27 on the opposite side of the coupler, the length of the pin lever between crank arm 27 and

fulcrum 24 can be regulated to meet particular requirements free from the hampering restrictions attending the fulcruming of the pin lever on the adjacent side of the coupler or crank arm.

The operating lever 20 is shown extending past the coupler 14 with its crank arm 27 extending outwardly under pin lever 21 and sufficiently to intersect the pin lever during

10 pulling operations when the coupler and pin lever assume the positions indicated in broken lines in Fig. 1. The pin lever 21 has loose connection with the coupler pin 28 to permit lateral and longitudinal movements 15 of the coupler, but is itself restrained from endwise movement by virtue of its engagement with bracket 24. Bracket 24 is provided with an eye portion 29 adapted to receive the hook-shaped end 30 on the pin lever with which it is assembled before said bracket is secured to the car.

In its normal position of rest, the crank arm 27 is out of contact with the pin lever 21 as indicated in Figs. 2, 3 and 4, allowing the pin lever to respond to relative movements of the car and coupler without disturbing the operating lever 20. Upon rotation of operating lever 20 to lift coupler pin to the unlocked position indicated 25 in broken lines in Figs. 2 and 3, the crank arm 27 will engage pin lever 21, as indicated in broken lines in Fig. 4, and carry same upwardly until the pin reaches its unlocked position, after which the operating lever 30 handle 26 may be released and permitted to drop to the normal position of rest as shown in full lines in Fig. 3, allowing the pin lever to be supported in its elevated position by the raised coupler pin 28 until dropped by 35 the coupling impact of the cars.

From the foregoing it will be noted that

we have provided a mechanism in which all of the parts are positioned below the upper side of the car end member 11, approximately the normal floor line of the car, without 45 the use of bottom operating couplers, and in which the members are arranged to provide adequate leverage under all conditions of service.

What we claim is:

1. In an uncoupling mechanism for cars having a coupler and a relatively low platform, an operating member mounted for operation on one side of the coupler; a pin lifting lever fulcrumed on the opposite side 55 of said coupler and adapted for engagement with the operating member, said operating and pin lifting members extending with their adjacent ends past each other above said coupler and below the floor line of the 60 car.

2. In an uncoupling mechanism for cars having a coupler and a relatively low floor, a pin lifting lever fulcrumed to the car below the floor line at one side of the coupler 65 and restrained from endwise movement, an operating lever mounted on the opposite side of the coupler below the floor line and extending with its crank arm for engagement with the pin lifting lever, said pin 70 lifting lever being adapted to engage said crank arm at a point mediate its fulcrum point and the coupler and extending with its free end through the coupler pin.

In witness whereof we have hereunto set 75 our hands in the presence of two witnesses.

OSCAR HOCHBERG.
JOHN W. STEINMEYER.

Witnesses:

JOSEPHINE MITCHELL,
HOMER CARROLL.
